(57) **CLAIM**

The ornamental design for a keycap having lid, as shown and described.

DESCRIPTION

FIG. 1 is a perspective view of a keycap having lid showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded view thereof;

FIG. 9 is a front view thereof in a first usage state; and, FIG. 10 is a front view thereof in a second usage state.

The broken line portions of the keycap having lid represent unclaimed portions of the claimed design and form no part thereof.

In FIG. 8, the lid is disassembled from the bottom of the keycap. In FIG. 9, the bottom of the keycap is configured with a rubber dome, and the lid is configured to protect the rubber dome. In FIG. 10, the bottom of the keycap is configured with a spring, and the lid is configured to protect the spring.
